UNITED STATES PATENT OFFICE.

JAMES DAVIDSON, OF TORONTO, ONTARIO, CANADA.

EASE-UP MOTION FOR THE TENSION-FALLERS OF SPINNING-MULES.

1,304,664.

Specification of Letters Patent.

Patented May 27, 1919.

Application filed April 17, 1918. Serial No. 229,068.

To all whom it may concern:

Be it known that I, JAMES DAVIDSON, of the city of Toronto, in the county of York and Province of Ontario, Dominion of Canada, have invented certain new and useful improvements in Ease-Up Motions for the Tension-Fallers of Spinning-Mules; and I hereby declare that the following is a full, clear, and exact description of the same.

10 This invention relates to an ease-up motion for the tension mechanism of a spinning mule, the object of the invention being to construct and arrange the sliding incline that it will so control the descent of the ease-up shoe and tension weights during the "backing off" motion of the spinning mule, as to prevent the breaking of the yarn, as hereinafter described and particularly pointed out in the claims.

20 For an understanding of the invention, reference is to be had to the following description and to the accompanying drawings, in which:

25 Figure 1, is a fragmentary rear elevational view showing the guide and tension shafts, and their respective fallers, and related parts, in the neutral position;

30 Fig. 2, is a sectional elevational view on the line *a*—*a*, Fig. 1, showing the same parts in full lines in the neutral position, and in dotted lines in the "backing off" position;

35 Fig. 3, is a side elevational view of the sliding incline for the ease-up shoe of the tension mechanism, showing it at the limit of its in-movement;

Fig. 4, is a rear elevational view of the parts shown in Fig. 3;

40 Fig. 5, is a detail sectional elevational view on the line *b*—*b*, Fig. 1, of the guide and tension fallers, the ease-up shoe, and the connecting rod and lever for the tension faller rock shaft, in the neutral position, and the sliding incline engaged by the ease-up shoe; and,

45 Fig. 6, is a similar view to Fig. 5, showing the position of the same parts when the mule is "backed off."

50 *a* represents the carriage; *b* represents an arm secured to the carriage; *c* represents the guide faller shaft, and *d* represents the tension faller shaft, both of which are journaled in the arm *b*. Fixed on the guide faller shaft *c* is the guide faller *e*, and fixed on the tension faller shaft *d*, is the tension faller *f*.

Encircling the guide and tension faller shafts *c* and *d*, is a casting *g*, formed with a toothed segment *h*, partly surrounding the guide faller shaft *c*. Encircling the guide faller shaft *c*, is a casting *i*, to which is connected the faller lock *j*, formed with a toothed segment *k*, meshing with the toothed segment *h*. Fixed on the tension faller shaft *d*, is an arm *l*, having at its outer end a grooved segment *m*, to which is connected the chain *o*, and suspended from the chain *o*, are the tension weights *p* and brace *q*, the brace being below the tension weights. Connecting the faller lock *j* with the brace *q*, is a chain *s* and wire *t*, to uphold the brace and tension weights when the guide and tension fallers are in their neutral position. Secured to the guide faller shaft *c*, is a leather strap *u*, and attached to the strap *u*, is the guide faller spring *v*, the lower end of the spring *v* being attached to a casting *w* at the lower end of the arm *b*. The tension faller shaft *d* is provided with a lever *d''*, to which is pivotally connected a rod *e''*, attached at its lower end to an ease-up shoe *f''*, which rides on the sliding incline when the spinning mule is in the "backing-off" position.

With the exception of the sliding incline, the above enumerated parts are similar to those in general use on spinning mules of the Johnson and Bassett, or Davis and Furber types.

The sliding incline, however, is essentially different in its structural character, operation, and purpose, from any other incline which has been previously employed in connection with the tension mechanism, and, as shown in the drawings, consists of a stationary slide-way *a'*, arranged lengthwise of the in and out run of the carriage, and approximately at the limit of the out run. Movable in the slide-way *a'*, is a block *b'* having an elongated vertical groove or slot *c'*. Connected to the block *b'*, and to the slide-way *a'*, is a spring or springs *d'*, to resist the movement of the block in the direction of the out run of the carriage, and to cause the movement of the block in the direction of the in run of the carriage, when moving back to its neutral position.

Within the inward end of the slide-way *a'*, is an adjustable stop *e'* to arrest the movement of the block *b'* in an inward direction, the purpose of the adjustment being to cor-

rectly regulate the movement of the sliding incline to the "backing off" motion of the mule.

Carried by the block b' , is the incline f' , provided with a vertical arm g' engaging the side of the block b' , and passing through the arm g' and through the groove or slot c' is a clamping bolt h' by which the incline is secured to the block.

10 By means of the arm g' , clamping bolt h' , and groove or slot c' , the apex of the incline can be adjusted to any predetermined height within the range of the groove or slot c' to compensate for variations in the level of the

15 floor.

Depending from the underside of the incline f' , near its lower end, is a lug i' , which engages the stop e' to arrest the forward movement of the block and the incline during the inrun of the sliding incline with the carriage.

20 During the outrun of the carriage, the ease-up shoe f'' engages the incline f' and moves it in the direction of the outrun of the carriage to the limit of movement, the spring or springs d'' maintaining the incline constantly in contact with the ease-up shoe.

25 During the outrun of the carriage, the guide and tension fallers, and their related parts, including the ease-up shoe, are in their neutral position, as shown in Fig. 5 of the drawings, and in this position, the ease-up shoe is engaging the incline near its apex.

30 When the mule "backs off", the guide and tension fallers, the faller lock, and the ease-up shoe and tension weights, move from the position shown in full lines in Fig. 2, to that shown in dotted lines in the same figure, and during this movement, the ease-up shoe 35 pushes the sliding incline in an outrun direction, as indicated by arrow in Fig. 5, before the spinning mule starts its inrun.

35 When the mule has started its inrun, the sliding incline moves inwardly with it until the lug i' engages the stop e' and arrests its continued movement in an inward direction.

40 By maintaining the sliding incline in contact with the ease-up shoe during the "backing off" movement, and arranging the sliding incline so that it will move in the direction of the outrun of the carriage during the descent of the ease-up shoe, it is possible to so control the "backing off" of the spinning mule as to prevent any sudden or irregular movement of the tension fallers, and thus overcome the tendency of the tension fallers to break the yarn through the sudden application of the tension; which is the 45 essential purpose of the invention.

40 An advantage arising from the use of the sliding incline, is the ability to apply greater weight to the tension fallers than was possible by the use of the stationary incline, and this increased weight enables the spinning mule to wind the yarn tightly on the bobbins,

and thereby materially increase the quantity of yarn to the set.

Having thus fully described the nature of my invention, what I claim as new and desire to secure by Letters Patent, is:—

1. In a spinning mule, the combination with the carriage, the tension shaft and faller, and the tension means for the tension shaft, of an ease-up motion for the tension shaft, comprising a shoe connected with the tension shaft, a sliding support engaged by and movable with the shoe during the outrun of the carriage, and self-movable with the shoe during a portion of the inrun of the carriage.

2. In a spinning mule, the combination with the carriage, the tension shaft and faller, and the tension means for the tension shaft, of an ease-up motion consisting of a shoe connected with the tension shaft, a sliding support engaged by and movable with the shoe when approaching the limit of movement of the outrun of the carriage, and means for causing the reverse movement of the sliding support and maintaining it in contact with the shoe during a portion of the inrun of the carriage.

3. In a spinning mule, the combination with the carriage, the tension shaft and faller, and the tension means for the tension shaft, of an ease-up motion consisting of a shoe connected with the tension shaft, a slideway arranged lengthwise of the in and out run of the carriage, and approximately at the limit of the outrun, a sliding support movable in the slideway, and engaged by and movable with the shoe when approaching the limit of movement of the outrun of the carriage, and means causing the reverse movement of the support and maintaining it in contact with the shoe during a portion of the inrun of the carriage.

4. In a spinning mule, the combination with the carriage, the tension shaft and faller, and the tension means and shoe for the tension shaft, of a stationary slideway arranged lengthwise of the in and out run of the carriage and approximately at the limit of the outrun, a sliding incline movable in the slideway, engaged by and movable with the shoe when approaching the limit of movement of the outrun of the carriage, and means for causing the reverse movement of the incline and maintaining it in contact with the shoe during a portion of the inrun of the carriage.

5. In a spinning mule, the combination with the carriage, the tension shaft and faller, and the tension means and shoe for the tension shaft, of an ease-up motion consisting of a slideway arranged lengthwise of the in and out run of the carriage, and approximately at the limit of the outrun, a sliding support movable in the slideway, and engaged by and movable with the shoe when

- approaching the limit of movement of the outrun of the carriage, means causing the reverse movement of the support and maintaining it in contact with the shoe during a portion of the inrun of the carriage, and means for stopping the support when it has reached the limit of its in-movement. 5
6. In a spinning mule, the combination with the carriage, the tension shaft and faller, and the tension means and shoe for the tension shaft, of a stationary slideway arranged lengthwise of the in and out run of the carriage, and approximately at the limit of the outrun, a sliding incline movable in the slideway, engaged by and movable with the shoe when approaching the limit of movement of the outrun of the carriage, means for causing the reverse movement of the incline and maintaining it in contact with 10
- 15 the shoe during a portion of the inrun of the carriage, and means for stopping the support when it has reached the limit of its in-movement. 20
7. In a spinning mule, the combination with the carriage, the tension shaft and faller, and the tension means and shoe for the tension shaft, of an ease-up motion consisting of a slideway arranged lengthwise of the in and out run of the carriage, and approximately at the limit of the outrun, a sliding support movable in the slideway, and engaged by and movable with the shoe when approaching the limit of movement of the outrun of the carriage, means causing the reverse movement of the support and maintaining it in contact with the shoe during a portion of the inrun of the carriage, and adjustable means for stopping the support when it has reached the limit of its in-movement. 25
- 30
- 35
- 40
8. In a spinning mule, the combination with the carriage, the tension shaft and faller, and the tension means and shoe for the tension shaft, of a stationary slideway arranged lengthwise of the in and out run of the carriage, and approximately at the limit of the outrun, a sliding incline movable in the slideway, engaged by and movable with the shoe when approaching the limit of movement of the outrun of the carriage, and means for causing the reverse movement of the incline and maintaining it in contact with the shoe during a portion of the inrun of the carriage, and adjustable means for stopping the support when it has reached the limit of its in-movement. 45
- 50
- of the incline and maintaining it in contact with the shoe during a portion of the inrun of the carriage, and adjustable means for stopping the incline when it has reached the limit of its in-movement. 55
9. In a spinning mule, the combination with the carriage, the tension shaft and faller, and the tension means and shoe for the tension shaft, of a stationary slideway arranged lengthwise of the in and out run of the carriage, and approximately at the limit of the outrun, a block movable in the slideway having an elongated vertical slot, an incline carried by the block and provided with a vertical arm engaging the side of the block, clamping means passing through the arm and block to allow of the vertical adjustment of the incline, an adjustable stop in the slideway, a stop carried by the incline 60
- 65
- 70
- 75
- engaging with the adjustable stop, and springs connected to the block to resist the movement of the block in the direction of the outrun of the carriage and to cause the movement of the block in the direction of the inrun of the carriage when moving back to its neutral position. 80
10. An ease-up motion for a spinning mule, comprising a stationary slideway arranged lengthwise of the in and out run of the carriage, and approximately at the limit of the outrun, a block movable in the slideway having an elongated vertical slot, an incline carried by the block and provided with a vertical arm engaging the side of the block, 85
- 85
- 90
- 95
- a vertical arm engaging the side of the block, clamping means passing through the arm and block to allow of the vertical adjustment of the incline, an adjustable stop in the slideway, a stop carried by the incline engaging with the adjustable stop, and springs connected to the block to resist the movement of the block in the direction of the outrun of the carriage and to cause the movement of the block in the direction of the inrun of the carriage when moving back to its neutral position. 90
